UNITED STATES PATENT OFFICE

EDMOND CHARLES LE FRANÇOIS, OF CLAMART, FRANCE, ASSIGNOR TO GENERAL ELECTRIC COMPANY, A CORPORATION OF NEW YORK

STEP-BY-STEP DEVICE

Application filed October 12, 1927, Serial No. 225,782, and in France November 2, 1926.

The present invention relates to devices operable step-by-step, through a series of definite positions and relates more particularly to improvements in electrical controllers of the 5 type such as are ordinarily used in trolley cars and the like.

One of the principal objects of the present invention is to provide improved means for insuring the step-by-step operation of controllers or other devices in one direction 10 through their various operating positions while permitting free and unrestrained return movement thereof.

With the preferred form of mechanism of 15 the present invention the enforced step-by-step operation of the controller is obtained by means of a sliding finger which preferably is carried by the operating handle of the controller and is guided between a double row of 20 stationary stops arranged so as to temporarily block further rotation of the controller handle at the end of each step. The arrangement of the finger and stops, however, is such that the controller always is free for movement in 25 the return direction.

The arrangement of the finger and stops will be better understood from the following drawing in which Fig. 1 illustrates a controller handle provided with a step-by-step 30 latching mechanism in accordance with the present invention, certain parts of the handle being broken away in order to more clearly reveal the detailed construction of the step-by-step mechanism; Fig. 2 is a plan view 35 showing the arrangement of the stationary stops with which the locking mechanism carried by the handle cooperates to assure step-by-step movement of the handle in one direction and free movement thereof in the other 40 direction.

In Fig. 1 the controller handle 10 is provided with a hand operating knob 11 and is suitably secured to the rotatable operating shaft 12 of the controller 13. The detailed 45 construction of the controller is not of the essence of the present invention and only the top portion thereof has been shown for the sake of clarity. The controller handle 10 is, in accordance with the usual practice, formed 50 in the shape of a channel providing a hollow

central space within which the improved step-by-step latching mechanism 14 readily may be mounted. As shown in Fig. 1, the latch mechanism 14 comprises a shaft 15 which is free to reciprocate in the bearings 16 and 17 55 mounted respectively in the cross-webs 18 and 19 extending between the channel sides of the handle 10. A sliding member 20 carries the locking finger 21 and is mounted upon the shaft 15. The locking finger 21, preferably is 60 of prismatic form, as indicated diagrammatically in Fig. 2.

Each of the bearings 16 and 17 is mounted in the corresponding webs 18 and 19 so as to permit movement thereof in the axial direction of the shaft 15. Thus the bearings 16 and 17 serve as spacing elements to maintain the sliding member 20 carrying the locking pin 21 in the central position between the ends of stops 22 and 23 provided on top of controller 13, as shown in Fig. 1. Thus in case the pin 21 is moved to the left so as to engage with the bearing 16, the bearing exerts pressure upon the collar 24 which is secured to the left-hand end of the shaft 15 and thereby compresses the spring 25 which is interposed between the end of the bearing 17 and the adjusting nuts 26. If, on the other hand, the pin 21 is moved to the right, this carries the sliding member 20 into engagement with the bearing 17 thereby again compressing the spring 25. In this way the spring 25 always serves to bring the finger 21 back into its normal position intermediate the ends of stops 22 and 23. 75

As indicated diagrammatically in Fig. 2, the locking member 21 is arranged to cooperate with a double row of angularly displaced stops 22, 22a, 22b, 23, 23a, 23b, which are mounted on top of the controller 13 in the path of movement of the locking finger so as to function in the following manner: The stops, 22, 22a, 22b, each serve to guide the finger 21 into abutting engagement with the next adjacent stops in the other row. Thus when the handle 10 of the controller is operated in a clockwise direction as indicated by the arrows, the finger 21 slides between the stops 22 and 23. As the handle 10 is moved rapidly, the finger 21 is brought into abutting 85 90 95 100

engagement with the end of the stop 23a, thus effectively arresting the further advancement of the handle. If, however, the operator releases the pressure on the handle, the pressure between the finger 21 and the end of the stop 23a decreases and finger 21 consequently returns to the intermediate position indicated as II in the drawing in accordance with its bias. In this position of the finger 21, the handle 10 again is free for advancement 5 over the next step of the controller. During this movement the finger 21 passes between the stops 22a and 23a until it is arrested by striking against the end of the stop 23b. Thus the advance of handle 10 again is 10 blocked and in order to continue its advancement the operator must again decrease the pressure of the finger 21 against the stop 23b in order that the finger 10 may return to the 15 normal mid-position. The step-by-step advancement of the handle 10 may be continued in a similar manner with any number of additional stops not shown in the drawing.

Thus it will be seen that it is impossible to 20 pass rapidly through more than one step of the controller and that the operator is thus constrained by the improved mechanism of the present invention to "mark the steps".

With the prismatic form of the finger 21 25 and the angular arrangement of the stops indicated in Fig. 2 it will be apparent that the handle 10 always is free for movement in the reverse direction. This is due to the fact that the finger 21 runs freely on the 30 outside of the stop 22, 22a and 22b, similar to a ratchet wheel and thus permits the controller handle to be brought back rapidly 35 into its initial position.

It will be observed that the handle 10 is 40 provided on its upper side with a headed bolt 27 which is capable of sliding in the slot 28 located above the shaft 15. The bolt 15 is provided with a spring pressed button 29 having the lower end of suitable form to fit 45 into either of the two recesses 30 and 31. Thus the bolt 27 may occupy either the position shown in the drawing or the position in which the end of the button 29 engages with the right-hand recess 31.

With the bolt 29 in the left-hand position 50 as shown the head of the bolt is out of engagement with the upstanding shoulder 32 on the sliding member 20 carrying the finger 21 and hence has no action thereon. If, on 55 the other hand, the bolt 27 is moved into the right-hand position the head of the bolt engages with the shoulder 32 formed on top of the sliding member 20, thus forcing the member 20, together with the finger 21, to the 60 right so as to carry the finger 21 entirely out of latching relation with the stops 22 and 23. This, of course, permits free movement 65 of the controller handle as desired and may be useful in case the controller is used for regenerative braking. In this service the pro-

tective resistance usually connected in series with the motors preferably is short-circuited as rapidly as possible when the counter electromotive force on the motor equals the line potential.

While the improved step-by-step latching mechanism of the invention has been described as applied to the handle of a railway controller, it will be evident that the mechanism can be applied with equal advantage 70 to other devices such as automatic motor starters and the like. Moreover, various changes in the detailed construction of the apparatus will occur to those skilled in the art without departing from the spirit and 75 scope of the invention.

What I claim as new and desire to secure by Letters Patent of the United States, is:—

1. The combination of a device having a 80 movable member operable through a series of positions, a relative movable member slidably connected with the first movable member for movement between two positions thereon, a row of angularly displaced elements disposed in the path of movement of said relatively movable member for effecting movement thereof to one of said positions upon movement of the first member in one direction between said positions and to the 85 other of said positions upon movement of the first member in the other direction between said positions, and a series of stops disposed to be successively engaged upon movement of the second member to said one 90 of said positions thereby to insure step-by-step movement of the first member in said one direction between said positions.

2. The combination of a device having a 95 movable member operable each way through a series of positions, a relatively movable member slidably connected with the first movable member for corresponding movement each way therewith and relative transverse movement, and cooperating rows of 100 angularly displaced guides and stops disposed in the path of movement of said relatively movable member with each guide arranged to guide the relatively movable member transversely into abutting engagement with the next adjacent stop to arrest the first member in each of a plurality of its positions upon movement thereof in one direction and to guide the relatively movable member transversely out of engagement 110 with the stops to permit unrestrained movement of the first member in the other direction.

3. The combination of a device having a 115 member rotatable each way between a plurality of angular positions, a locking member mounted upon the first member for simultaneous angular movement each way therewith and for movement between two 120 positions in a radial direction, means for 125

biasing said locking member to an intermediate radial position, and a plurality of stationary elements located in the path of movement of said second member, one portion thereof being disposed to effect movement of the locking member from said intermediate position to each of said radial positions, and another portion being disposed to be successively engaged and disengaged 5 when the locking member is operated to one of said radial positions thereby to insure step-by-step movement of the first member between adjacent angular positions.

4. The combination of a device having a member operable between a plurality of definite positions, a locking finger slidably mounted upon said member for movement between a plurality of positions, means for biasing said finger to an intermediate one of 10 said positions, and a double row of angularly displaced stationary elements located in the path of movement of said locking finger with the elements in one row arranged to operate the finger into a position to abut 15 against the next succeeding element in the other row upon movement of the first member in one direction to each definite position and to operate the finger to a different position upon movement of the first member 20 in the other direction and thereby permit unrestrained movement of the member in the other direction.

5. The combination with a controller having a movable operating handle, of a step-by-step latching mechanism for the controller handle including a series of stops and a relatively movable member slidably mounted for movement transverse to the direction of movement of the controller handle, and 35 a plurality of guides arranged in staggered relation to be successively engaged by said member to move the same out of latching relation with the said stops upon movement of the controller handle in one direction between adjacent operative positions.

6. The combination with a controller having a rotatable operating handle, of a locking mechanism for the controller handle comprising a finger slidably mounted for 40 movement longitudinally of the controller handle between fixed limits, means for biasing the finger to an intermediate position between said limits, and cooperating rows of guides and stops located in staggered relation to be successively engaged by the finger to insure step-by-step operation of the controller handle between adjacent positions in one direction and unrestrained operation thereof in the other direction.

7. The combination of a controller having an operating handle rotatable through a plurality of definite operating positions, a locking mechanism for insuring a step-by-step operation of the controller handle to each 45 of said operating positions in one direction

and unrestrained movement of the controller handle in the other direction comprising a locking finger slidably mounted upon the controller handle to permit movement thereof in a radial direction upon rotation of the handle, a double row of cooperating elements mounted on top of the controller and each extending transverse the path of movement of said locking finger, with the ends of adjacent elements in each row in substantially circular alignment, means for biasing said locking finger to a position intermediate the ends of the elements in one of said rows, and means adjustable at will to maintain the locking finger out of engagement with the 70 elements.

In witness whereof, I have hereunto set my hand this 3rd day of August 1927.

LE FRANÇOIS, EDMOND CHARLES.
